UNITED STATES PATENT OFFICE.

WILLIAM H. PAVITT, JR., OF NEW YORK, N. Y., ASSIGNOR OF ONE-THIRD TO LOUIS WILPUTTE AND TWO-THIRDS TO ALICE A. WILPUTTE, BOTH OF NEW ROCHELLE, NEW YORK.

COAL-LORRY.

1,363,008.

Specification of Letters Patent. Patented Dec. 21, 1920.

Application filed January 20, 1919. Serial No. 272,032.

To all whom it may concern:

Be it known that I, WILLIAM H. PAVITT, Jr., a citizen of the United States, and resident of New York, in the county of New York and State of New York, have invented certain new and useful Improvements in Coal-Lorries, of which the following is a specification.

My present invention consists in an improved coal lorry adapted for charging the retorts or oven chambers of coke ovens over which the lorry runs, and the general object of my invention is to provide means for substantially eliminating the spillage of coal on the oven top at the margins of its charging holes in the oven charging operation. The various features of novelty which characterize my invention are pointed out with particularity in the claims annexed to and forming a part of this specification; for a better understanding of the invention, however, and the advantages possessed by it reference should be had to the accompanying drawings and descriptive matter in which I have illustrated and described a preferred embodiment of my invention.

Of the drawings Figure 1 is an elevation of a coal charge lorry and a portion of the oven structure over which it runs, the latter being in section.

Fig. 2 is a section of the line 2—2 of Fig. 1.

Fig. 3 is a diagrammatic plan of a portion of the lorry.

Fig. 4 is an elevation, in section on the line 4—4 of Fig. 3, of a portion of the lorry.

Fig. 5 is a section on the line 5—5 of Fig. 4.

In the drawings I have illustrated the use of my invention in a coal charging lorry D of the type commonly employed in charging coal into by-product coking ovens having horizontal coking chambers. In the drawings A represents the coke oven structure proper and A' one of the coking chambers therein. At distributed points along the length of the chamber A' charging holes A² are formed in the roof of the oven chamber; as shown there are four of these charging holes. The charging holes are normally closed, by removable cover plates C, seated in charging hole castings B which are embedded in the masonry of the oven structure

proper. The coal charging lorry D which runs upon track rails A³ mounted on the roof of the oven structure, is provided with hoppers D¹, D², D³ and D⁴, one for each of the charging orifices A². Each hopper, as shown comprises an upper cylindrical portion, an intermediate conical portion, and a tubular bottom portion D⁵, the latter registering with the corresponding charging hole A² in the oven charging operation. Trunnions D⁶ are carried by the tubular portion D⁵ of each hopper, and the passage of coal out of the hopper through the discharge orifice formed by the open lower end of its tubular portion D⁵, is controlled by a gate or valve which has arms pivoted on the corresponding pair of trunnions D⁶. Each gate E is connected to suitable operating mechanism; the connections shown comprise a link E², a crank arm E³ and a crank shaft E⁴. In so far as above described, the coal lorry shown embodies nothing novel with me, but on the contrary is of a type well known and extensively used.

To prevent the spillage of coal on the top of the oven at the margin of the charging holes in the oven charging operation, I provide each hopper with a funnel like member F having arms F' journaled on the corresponding trunnions D⁶ which are elongated for the purpose. In the oven charging position each funnel F is coaxial with the tubular portion D⁵ of the corresponding hopper, and has its upper end at or about the level of the lower end of the hopper part D⁵. The lower end of the funnel is then but an inch or so above the top of the oven roof. When the lorry is being moved over the oven roof, and when the charging hole covers C are being moved into and out of place the funnels F are swung into the position shown in Fig. 1 and in dotted lines in Fig. 4. The then lowermost portion of a funnel F is at, or as shown is somewhat above the level of the lowermost portion of the corresponding gate E when the latter is in its normal closed position. To thus adjust the funnels F, I have provided in the particular construction shown, an extension F² on one arm F' of each funnel F, and have connected this extension by a link F³ shown as including a turn buckle for length adjustment, to a crank arm F⁴ carried by a rock shaft journaled in the frame

work of the lorry. As shown, there are two of these rock shafts, one marked F^5 and one F^{50} , which are in alinement with one another. The funnels F for the hoppers D^1 , D^2 , and D^3 are connected to the rock shaft F^5 , and the funnel F of the hopper D^4 is connected to the rock shaft E^{50} . The rock shaft F^5 may be manually rotated by means of a link F^6 connecting an arm carried by 10 the rock shaft to an operating lever F^7 fulcrumed at D^7 and working along a quadrant D^8 provided with notches by which the lever may be locked in either of its two positions. The rock shaft F^{50} is similarly connected 15 by a link F^{60} to an operating lever F^{70} working along a quadrant D^8 . The levers F^7 and F^{70} are located on the operating platform or in the cab of the lorry as conditions make desirable. By making the funnel 20 F for the hopper D^4 operate separately from the other funnels it is possible to completely discharge the hoppers D^1 , D^2 , and D^3 , and to replace the covers C for the corresponding charging holes A^2 before the hopper D^4 25 is completely discharged. This avoids difficulty from escaping gases as will be readily recognized by those skilled in the art. To make it easier to swing the funnels F back and forth between the dotted and full 30 line positions shown in Fig. 4, I attach an adjustable counter weight F^8 to each funnel.

With the funnels F in their elevated positions there is sufficient clearness between the bottoms of the hoppers and the top of the 35 oven structure to minimize interference from tools or other small objects lying on the top of the oven as the lorry is moved along the rails A^3 . With the funnels F in their lowered positions the lateral flow of 40 coal out on to the top of the oven at the margins of the charging holes is substantially minimized since the bottoms of the funnels F may then be within an inch or so of the level of the top of the oven. Any coal passing 45 out of a hopper and not directly entering the corresponding orifice A^2 , will collect in the cavity B^1 provided in the charging hole casting B at the margin of the orifice in the latter. By the use of the funnel it is 50 thus possible to avoid the spillage of coal on to the top of the oven which invariably occurs when the coal is allowed to fall without any guiding inclosure from the bottom of the hopper when the latter is elevated, as it 55 must be in practice, a few inches from the top of the oven. The spillage of coal on the oven top under such conditions is augmented by the fact that the coal is ordinarily finely crushed and when it impinges against the 60 top of the oven at the margin of the charging holes it tends to spread out and under these conditions has no appreciable or definite angle of repose. The pivoted funnels

shown are of greater mechanical simplicity and more reliable than the telescopic funnels 65 or hopper sections which it has been heretofore proposed to use on some coal charging lorries.

While in accordance with the provisions of the statutes I have illustrated and described the best embodiments of my invention now known to me, it will be apparent to those skilled in the art that changes may be made in the form of apparatus shown without departing from the spirit of my invention as set forth in the appended claims, and that certain features of my invention may sometimes be used to advantage without a corresponding use of other features.

Having now described my invention, what 80 I claim as new and desire to secure by Letters Patent, is:

1. A coke oven coal charging lorry having a hopper with a bottom discharge orifice and in combination therewith a funnel pivoted to the lorry to swing back and forth between a lower position in which it is beneath said orifice and an upper position at the side of the orifice.

2. A coke oven coal charging lorry having a hopper with a bottom discharge orifice and a valve controlling the discharge through said orifice, and in combination therewith, a funnel separate from said valve and pivoted to the lorry to swing back and forth between a lower position in which it is beneath said orifice and an upper position in which it is at the side of the orifice.

3. A coke oven coal charging lorry having a hopper with a bottom discharge orifice and provided with trunnions at opposite sides of said orifice, a gate valve pivoted on said trunnions and controlling said orifice and a funnel separate from said valve and also pivoted on said trunnions and adapted to swing back and forth between a lower position in which it is beneath said orifice and an upper position in which it is at the side of the orifice.

4. A coke oven coal charging lorry having 110 a plurality of hoppers arranged side by side, each with a bottom discharge orifice and a valve controlling the discharge through said orifice and in combination therewith a funnel for each hopper separate from the valve 115 thereof and pivoted to the lorry to swing back and forth between a lower position in which it is beneath the corresponding hopper orifice and an upper position in which it is at the side of said orifice and operating 120 connections to said funnels whereby the funnel for the hopper at one end of the lorry may be operated independently of the other funnels.
